Primary Examiner — Sanjeev Paul(74) *Attorney, Agent, or Firm* — King & Partners, PLC(57) **CLAIM**

The ornamental design for a pillow, as shown and described.

DESCRIPTION

FIG. 1 is a perspective view of a pillow, showing my new design in an open configuration.

FIG. 2 is a top plan view of the pillow of FIG. 1.

FIG. 3 is a bottom plan view of the pillow of FIG. 1.

FIG. 4 is a right side elevation of the pillow of FIG. 1. The left side elevation is a mirror image of the right side elevation.

FIG. 5 is a front side elevation of the pillow of FIG. 1. The rear side elevation is a mirror image of the front side elevation.

FIG. 6 is a right side elevation of the pillow of FIG. 1 shown in a partially folded configuration.

FIG. 7 is a perspective view of the pillow of FIG. 1 shown in a folded configuration.

FIG. 8 is a top plan view of the pillow of FIG. 7.

FIG. 9 is a bottom plan view of the pillow of FIG. 7.

FIG. 10 is a right side elevation of the pillow of FIG. 7.

FIG. 11 is a left side elevation of the pillow of FIG. 7.

FIG. 12 is a front side elevation of the pillow of FIG. 7; and, FIG. 13 is a rear side elevation of the pillow of FIG. 7.
